MACHINE FOR PRODUCING CONGEALED
SUBSTANCES

William H. Taylor, Muskego, Wis., assignor to
The Vilter Manufacturing Company, Milwaukee,
Wis., a corporation of Wisconsin

Application February 2, 1935, Serial No. 4,667

14 Claims. (Cl. 62—106)

The present invention relates in general to improvements in the art of congealing fluent substances, and relates more specifically to improvements in the construction and operation of machines for producing ice.

An object of the invention is to provide an improved machine for producing congealed substances, which is simple in construction and efficient in operation.

10 Another object of the invention is to provide a new and useful ice making machine which is compact and durable in structure, and which has enormous capacity considering the size of the unit.

15 A further object of the invention is to provide an improved liquid congealing unit of extremely simple construction which can be manufactured and operated at relatively low cost, and the capacity of which may be readily altered.

20 Still another object of the invention is to provide an automatically functioning slush-ice producing structure which can be disposed in any desired position, and even immersed in liquid, if so desired.

25 An additional object of the invention is to provide an ice machine having readily machinable cooling surfaces of extended area, and provided with simple means for removing the congealed material therefrom.

30 A further object of the invention is to provide improved means for subjecting the ice-forming surfaces of a machine to cooling action, without danger of escape of the refrigerating medium.

These and other objects and advantages of the 35 present improvement will be apparent from the following detailed description.

A clear conception of an embodiment of the invention, and of the mode of constructing and of 40 operating liquid congealing machines built in accordance with the improvement, may be had by referring to the drawing accompanying and forming a part of this specification, in which like reference characters designate the same or similar parts in the various views.

45 Fig. 1 is a relatively diagrammatic central vertical longitudinal section through one of the improved machines for producing congealed substances;

50 Fig. 2 is a transverse vertical section through the machine of Fig. 1, taken along the line 2—2;

and

55 Fig. 3 is a transverse central vertical section through the machine, taken along the line 3—3 of Fig. 1.

While the invention has been shown and described herein as being specifically embodied in a machine for producing slush-ice from water, it is not desired to unnecessarily restrict the scope by such specific embodiment, since the improved features may be readily applicable with like advantage to other types of machines for producing congealed substances.

Referring to the drawing, the improved ice making unit specifically shown comprises, in general, a main casing 5 composed of two end and two intermediate fixed sections 6 having spaced external cooling surfaces 7 and internal refrigerant confining chambers 8, and lower and upper refrigerant supply and exhaust headers 9, 10, 15 respectively, in open communication with the several chambers 8; a series of three revolving scrapers 11 disposed between adjacent cooling surfaces 7 of the successive casing sections 6 and having opposite cutting edges 12 cooperable with 20 the surfaces 7 to remove the successive ice films therefrom; a main shaft 13 journaled in bearings 14 secured to the end casing sections 6 and rotatably supporting the scrapers 11 for movement along the cooling surfaces 7; and one or more 25 liquid supply pipes 15 having orifices 16 for delivering sprays of water over the cooling surfaces 7 and against the revolving scrapers 11.

While the machine specifically illustrated has 30 four casing sections 6 cooperating with three revolving scrapers 11, the actual number of these sections and scrapers may obviously be reduced or increased to produce a unit of any desired capacity. The unit may also be disposed with the axis of the main shaft 13 either horizontal, 35 as shown, or vertical, or at an inclination; and the number of spray pipes 15 may be diminished or increased, or these pipes may be entirely omitted and the unit immersed in liquid sufficiently to maintain the cooling surfaces 7 or a portion thereof beneath the liquid level.

The casing sections 6 are all of like construction, and while the cooling or congealing surfaces 7 would preferably be formed plane, as shown, 45 these surfaces may obviously be frusto-conical if desired. The sections 6 are rigidly attached to the headers 9, 10 by cap-screws 17 and have lower and upper elongated openings 18 affording constant communication between the several chambers 8 and the headers. The refrigerant supply header 9 has a refrigerant supply pipe 19 which may be provided with a suitable control valve, and the exhaust header 10 has a discharge pipe 20 50 55

formed to deliver the spent refrigerating medium from the unit.

The several scrapers 11 are removably secured to carrier arms 21 by means of screws 22 in order to permit replacement or sharpening of these scrapers; and the scraper carrier arms 21 are adjustably secured to the main shaft 13 by means of set-screws 23 so as to permit angular adjustment of the scrapers 11 about the shaft axis so as to secure most efficient distribution of the driving forces. The main driving shaft 13 may be provided with a propelling pulley 24 or other suitable driving means, and extends through enlarged central openings 25 in the several casing sections 6. In order to prevent congealed material from lodging in these openings 25, the portions of the shaft 13 within the openings are provided with helical scraping conveyors 26 which serve to remove and to expel congealed substance from the openings 25 during normal rotation of the shaft 13. The liquid supply pipes 15, when used, may be provided with regulating valves, and the orifices 16 are preferably so formed and located that they will maintain the cooling surfaces 7 abundantly supplied with fresh liquid.

During the normal operation of the improved liquid congealing machine, the several surfaces 7 are being cooled by the admission of regulated quantities of fluent refrigerant from the pipe 19 and header 9 to the several cooling chambers 8, and the spent refrigerant is being withdrawn from these chambers through the header 10 and exhaust pipe 20. The cooling surfaces 7 are being supplied with abundant quantities of fresh liquid either from the pipes 15 or otherwise, and the scrapers 11 are being constantly revolved by the application of power to the pulley 24, so as to cause the cutting edges 12 thereof to constantly advance along and in close proximity to the cooling surfaces 7. The scrapers 11 thus function to constantly remove the films of ice formed upon the cooling surfaces 7, and the ice crystals thus removed are carried from the spaces between the successive casing sections 6 and are removed from the scrapers 11, by the excess liquid supplied. The mixture of liquid and ice crystals thus removed from the unit may be subsequently treated for the removal of excess liquid, and the entire unit may be housed within an enclosing casing in order to prevent excess melting of the removed ice crystals.

While the shaft 13 is being rotated, the scraper conveyors 26, disposed within the openings 25 of the sections 6, prevent congealed liquid from depositing within these openings, and in order to prevent excessive heating of the exterior of the unit, the outer surfaces of the end sections 6 and of the headers 9, 10 may be covered with insulation. By properly positioning the scrapers 11 about the driving shaft 13, the power consumption may be reduced to a minimum, and by regulating the rate of rotation and the admission of liquid and refrigerant, most efficient operating conditions may be readily established. The scrapers 11 are also readily removable for replacement or in order to sharpen the cutting edges 12 thereof, and the entire machine may obviously be readily assembled or dismantled. The normal operation of the machine is obviously automatic with the exception of the adjustments required in order to establish predetermined conditions of operation, and the unit obviously has enormous capacity considering the space occupied thereby. The capacity of the machine may also be increased or diminished by providing more

or less casing sections 6 and scrapers 11, and the mechanism, by virtue of its simplicity, can obviously be manufactured and operated at extremely moderate cost.

It should be understood that it is not desired to limit the invention to the exact details of construction and to the precise mode of operation herein shown and described, for various modifications within the scope of the claims may occur to persons skilled in the art.

It is claimed and desired to secure by Letters Patent:

1. In combination, a fixed casing having an external substantially plane cooling surface, means for cooling said surface to freezing temperature, means for delivering liquid to said surface, and a scraper movable over said surface to remove successive ice films therefrom.

2. In combination, a casing having spaced stationary cooling surfaces, means for subjecting said surfaces to cooling action, means for depositing liquid upon said surfaces, and a scraper movable between and along said surfaces to remove congealed substance therefrom.

3. In combination, a fixed casing having parallel cooling surfaces disposed about an axis, means for cooling said surfaces to freezing temperatures, means for depositing liquid upon said surfaces, and a scraper revolvable about said axis between said surfaces and having cutting edges movable in close proximity to and along said surfaces.

4. In combination, a casing having a series of sections provided with external cooling surfaces separated by an intervening space, means for subjecting said surfaces to freezing temperatures, means for supplying liquid to said surfaces, and a scraper movable about the central axis of said sections and having cutting edges movable in close proximity to and along said surfaces.

5. In combination, a casing comprising a series of detachably interconnected sections having external adjacent cooling surfaces, means for subjecting said surfaces to freezing temperatures, means for supplying liquid to said surfaces, and a scraper movable between adjacent sections or said casing in close proximity to said surfaces, said scrapers being adjustable relative to each other.

6. In combination, a casing comprising a series of sections having adjacent cooling surfaces, means for cooling said surfaces, means for supplying liquid to said surfaces, a scraper cooperable with said surfaces to remove ice deposits therefrom, a shaft extending through openings in said sections for revolving said scraper, and means associated with said shaft for preventing lodging of congealed substances within said openings.

7. In combination, a casing comprising a series of sections each having a refrigerant receiving chamber therein and an external cooling surface, headers for admitting refrigerant to and from said chambers, means for supplying liquid to said surfaces, and a scraper movable between adjacent cooling surfaces of said sections for removing congealed substances therefrom.

8. In combination, a casing comprising a series of sections each having a refrigerant receiving chamber therein and an external cooling surface, headers for admitting refrigerant to and from said chambers, means for supplying liquid to said surfaces, and a scraper revolvable between adjacent cooling surfaces of said sections for removing congealed substances therefrom.

9. In combination, a casing comprising a series

5 of sections having adjacent parallel external surfaces, means for cooling said surfaces, means for supplying liquid to said surfaces, a shaft extending centrally through said casing sections, and scrapers carried by said shaft and movable between said surfaces to remove congealed liquid therefrom.

10. In combination, a stationary casing having a series of openings therethrough bounded by parallel cooling surfaces, means for subjecting said surfaces to cooling action, means for supplying liquid to said surfaces, and a series of scrapers movable within said openings to remove congealed liquid from said surfaces.

15. 11. In combination, a stationary casing having a series of parallel openings therethrough each bounded on opposite sides by cooling surfaces, means for cooling said surfaces, means for supplying liquid to said surfaces from the exterior of said casing, and a series of scrapers revolvable within the successive openings to remove congealed liquid from said bounding surfaces thereof.

20. 12. In combination, a casing having a series of through openings each bounded by parallel cool-

5 ing surfaces, means for cooling said surfaces, means for supplying liquid to all portions of said surfaces, and a scraper movable within each of said openings and having cutting edges cooperable with the adjacent cooling surfaces, said scrapers being independently removable from within said openings.

13. In combination, a fixed casing having a series of parallel through openings each provided with parallel bounding surfaces, means for subjecting said surfaces to a cooling action, means for supplying liquid to said surfaces, and a scraper revolvable within each of said openings, each of said scrapers being adjustable and removable independently of others and having cutting edges 15 cooperable with the adjacent cooling surfaces.

14. In combination, a fixed casing having a pair of external cooling surfaces separated by an intervening space, means for cooling said surfaces, means for supplying liquid to said surfaces, and 20 an ice film remover movable in the space between said surfaces for simultaneously removing congealed substances from both surfaces.
